UNITED STATES PATENT OFFICE.

CHARLES E. KEARNS, OF BALTIMORE, MARYLAND.

HOVER.

Application filed February 3, 1923. Serial No. 616,683.

This invention relates to hovers, and especially to an electrically heated, automatically controlled, radiating hover.

One object of this invention is to provide an improved electrically heated hover with simple and effective means for automatically regulating the electric current, and thus automatically regulating the temperature within the living room of chamber of the 10 hover.

Another object is to provide a hover of this character with a chick-chamber or living room having a heat-radiating ceiling which simulates the action of the sun in radiating the heat-rays down on the backs of the chicks and thus properly heats their lungs and spines; this radiating plate or ceiling also constituting a partition which separates the chick-chamber from the heat-generating chamber in which latter is arranged the electric heating coils or continuous coil; this partition also separating the thermally controlled switch from the dust and other foreign matter which arises from 20 the chick-chamber; thus affording a protection against detriment to the action of the heating coil and switch.

Another object is to provide an improved thermally controlled switch which is also 30 manually controllable so as to compensate for various weather conditions or temperatures; also to provide a switch of this kind which is controllably connected with a well known thoroughly practical and effective, 35 yet comparatively low-priced thermostat which can be purchased from the open market.

A further object is to provide a device of 40 this character which includes a heat-insulated partition between the heating coil or unit and the switch-chamber; the space between the heat-insulated partition and the heat-conducting and radiating partition being slight so as to provide exceedingly efficient radiation of heat into the chick-chamber, also to minimize the electric energy necessary for producing the necessary heat-radiation.

Other objects and important features will 50 be pointed out or implied in the following details of description, in connection with the accompanying drawings in which,—

Fig. 1 is a vertical sectional view through the central part of a hover constructed according to this invention: Fig. 2 is an under

plan view of the heat-insulated partition, heating unit and switch-base, parts being broken away to show other parts: Fig. 3 is an enlarged or somewhat exaggerated detail section showing the different laminae of the heat-insulated partition: Fig. 4 is a detail showing, as an article of merchandise, the thermo-electric unit which includes the switch, the thermostat and the insulated or insulating connections therefor: Fig. 5 is 60 a perspective view (enlarged) of the switch-spring, its insulating nut and the controlling screw: Fig. 6 is a side elevation of the carbon-contact-holder and the carbon-contact: And Fig. 7 is a vertical sectional view 70 through the carbon-contact-holder, as seen at right angles to Fig. 6.

Referring to these drawings in detail, in which similar reference characters refer to similar parts throughout the several views:—

The roof or cover 1 is preferably conical or pyramidal and has at its apex an opening in which an internally insulated channel or vent 2 is secured by a nut 3 or other appropriate means. This vent also constitutes an inlet for the cable which includes the supply and return conductors 4 which have their outer terminals connected to an ordinary plug or lamp-socket connection 5. The inner terminals of the cable or conductors 4 are connected respectively to binding posts 6 and 7, the latter being also connected to one terminal of a heating coil or unit 8 which is stretched around an inner circular series and an outer circular series of insulating knobs 9 (see Fig. 2); and the other terminal of the heating unit 8 is connected to the switch-contact 10, of carbon, through the medium of the contact-holder or clamp 11 and its securing screw 12.

The conducting elements 6, 7 and 12 extend through an insulating plate or switch-base 13, and the screw or element 6 also combines with the screw 14 for securing the spring-arm 15 of the switch in place on its base 13. The switch-arm 15 is provided with a contact 16, preferably secured by a nut on a threaded shank that extends through an opening 17 (Fig. 5) of the metal strip 6 which constitutes the spring-arm of the switch. As the spring-arm is deflected upward, the switch is opened by separation of its contacts 10 and 16, and it automatically closes, when permitted, by the spring action constantly tending to close it. In 110

Fig. 4, the spring-switch is closed, but in Fig. 1 it is held open by the thermostat and a manually adjustable member or screw 19 which extends up through an opening 20 of the cover 1 and is provided with a knob or handle 21 by which it can be turned or lifted. The screw 19 is threaded in an insulating nut 22 which is united with the spring-arm 15 by means of screws or other appropriate means; the screw 19 also extending through a large opening in the arm 15; this opening providing a clear space around the screw 19, so that the screw is insulated from the arm 15, thereby eliminating danger of short-circuiting through this screw. The bracket 18^a, of the thermostat, is secured on the lower end of a metal tube 24, and the upper end of this tube extends through the switch-base 13 and is secured thereto by nuts (as shown) or by other appropriate means. The intermediate part of the tube 24 extends through an opening in lower partition or radiating plate 24 which is preferably of Bessemer black iron, and in order to avoid any possibility of making electrical contact between the plate 24 and the pipe 23, an insulating tube 25 is provided around the metal tube 23.

Screws or other appropriate means 26 may be employed for uniting the switch-base 13 to the heat-insulating partition 27, and this partition is preferably united with the radiating plate or partition 24 by means of screws 28 which extend therethrough and through insulating knobs 29 and through nuts, the latter securing them in place, and the knobs 29 serving as spacers between the partitions 24 and 27. Additional spacers 30 may be employed around screws or bolts 31 which secure the partitions 24 and 27 in position within the hollow cone or pyramid which constitutes the cover 1.

The partition 27 is preferably a laminated structure such as shown at the bottom of Fig. 2 and in Fig. 3, where a sheet-steel plate 32 (preferably galvanized) is the upper lamina; then, next, is a lamina or thin coating of water-glass 33; next, a sheet or plate 34 of asbestos or other heat-insulating material; and next or lowermost is a second lamina or coat 35 of water-glass; thus providing an efficient electric insulation as well as heat insulation.

The structure thus far described is supported, in spaced relation to the ground or floor on which the hover is used, by legs 35 which slant downward and outward from the rim of the cover where they are secured by screws or any other appropriate means. A wire hoop 36 rests on the upper outer surfaces of these legs, and the wall 38 of fabric or other flexible material is provided with a hem or channel through which this hoop extends for supporting the wall 38 and permitting it to be slid along the hoop's

circumference. The usual entrances are provided in the wall 38 by means of vertical slits or slashes.

The clamp 11 (Figs. 6 and 7) is formed of conducting material having a cylindrical outer surface. In its lower end is the threaded bore 11^a which receives the securing screw 12; in its upper end is the socket 11^b which holds the carbon-contact 10; a diametral bore 11^c provides slightly flexible elements on its opposite sides; a slot 11^d extends axially and diametrically through the body from the upper extremity to the opening 11^e, thus providing jaws on its opposite sides; and a screw 11^e is threaded in one jaw and extends through the other jaw and co-operates with these jaws to clamp the carbon-contact 10 and hold it in different adjustments with relation to the contact 16.

When the screw 19 is properly adjusted for a predetermined temperature in the chick-chamber, and when this temperature is exceeded or reached, the "wafer-thermostat" 18 expands upwardly until it lifts the screw 19 sufficiently to open the switch by separating its contacts 10 and 16, as shown in Fig. 1; thus stopping the generation of heat in the heating unit 8; so the chick-chamber immediately begins to cool; but before it has cooled to any detrimental extent, the thermostat retracts and permits the switch to automatically close; and thus the heat of the chick-chamber regulates itself through the thermally controlled switch.

The heating coil may be made of any appropriate kind of wire, and the coil, when stretched on the knobs 9, is preferably 84 inches long, for a hover whose radiating plate is 24 inches diameter. The "breathing spaces" between the convolutions of the coil is approximately as wide as the diameter of the wire, and the diameter of each convolution is preferably about five-thirty-seconds of an inch.

The cable which includes the conductors 4 is preferably tied into a knot at the nut 3 to prevent the terminals from being pulled loose from their binding posts, and an insulating washer 4^a is or may be provided to prevent wear of the insulation of the cable by the lower end of the inlet tube 2.

It is not intended to limit this invention to the exact construction and arrangement here shown, but changes may be made within scope of the inventive ideas as claimed and implied.

What I claim as my invention is:

1. The hover or brooder which includes a cover having thereunder a chick-chamber provided with a heat-radiating ceiling, a heating unit over and adjacent to said ceiling but spaced from the ceiling, conducting means through which said heating unit can

be electrically energized for generating heat and transmitting heat to said ceiling, a heat-insulating plate over and adjacent to but spaced from said heating unit and adapted 5 to deflect the heat down on the heat-radiating ceiling, said heat-radiating plate and heat-insulating plate and cover combining to form a substantially air-tight or draftless chamber in which the heating unit is 10 air-insulated, said conducting means including a switch, and means operable for opening and closing the switch when the temperature in the chick-chamber becomes sufficiently high.

15 2. The structure defined by claim 1, a hollow cover in which said heat-radiating plate and heat-insulating plate are secured in proper relation to form substantially closed chambers above and below the heat insulating plate, said switch being in and protected by the upper one of these chambers, said heating unit being in the lower one of these 20 chambers and thereby having its heated air confined to a considerable and beneficial extent in contact with said heat-radiating plate so as to efficiently impart heat to the latter.

30 3. The combination of a chick-chamber; a heat-radiating plate disposed horizontally over the chick-chamber in position to radiate heat into the chick-chamber; an insulating element supported by the said plate; and an electric conductor including a heating coil, a switch and binding posts, said 35 plate being provided with an inner series and an outer series of insulating supports on its lower side, said binding posts secured to said insulating element and extending from the lower side to the upper side of said 40 plate, said heating coil having its ends connected respectively to the lower ends of the binding posts and having its intermediate portion stretched around the insulating supports by reaching alternately from an 45 outer support to an inner support and thence to an outer support and so on substantially as shown, said switch being on the upper side of said insulating element

and having its terminals connected to the upper ends of the respective binding posts. 50

4. The combination of a chick-chamber, a heat-radiating plate disposed horizontally over the chick-chamber in position to radiate heat into the chick-chamber; an insulating element supported by said plate; and an 55 electric conductor including a heating unit, a switch and binding posts; said plate being provided with insulating supports on its lower side; said binding posts being secured to said insulating element and extending from the lower side to the upper side of said plate; said heating unit having its ends connected respectively to the lower ends of said binding posts and having its intermediate parts extending around said 60 insulating supports; said switch being on the upper side of said insulating element and having its terminals connected respectively to the upper ends of said binding posts. 70

5. The combination of a chick-chamber; a hollow cover therefor provided with an apex having a hole therethrough; an upper and a lower partition disposed horizontally in said cover and thus providing an upper 75 chamber and a lower chamber; electric conducting means including a plug-connection provided with a feed wire and a return wire, a switch having one terminal connected to one of the wires of plug connection, 80 and a heating unit having one terminal connected to the other wire of said plug connection, the other terminal of the heating unit being connected to the other terminal of said switch; said wires of the plug connection 85 extending through said apex; a thermostat in said chick-chamber and a manually adjustable switch-opening element extending through said cover and through said partitions into the path of expansion 90 of said thermostat; said heating unit being in said lower chamber, said switch being in said upper chamber.

In testimony whereof I affix my signature.

CHARLES E. KEARNS.
